UNITED STATES PATENT OFFICE.

MANLEY W. CLUXTON, OF CHICAGO, ILLINOIS.

METAL SHEET-PILING.

No. 909,549.

Specification of Letters Patent.

Patented Jan. 12, 1909.

Application filed March 28, 1908. Serial No. 423,838.

To all whom it may concern:

Be it known that I, MANLEY W. CLUXTON, a citizen of the United States, and a resident of Chicago, in the county of Cook and State 5 of Illinois, have invented certain new and useful Improvements in Metal Sheet-Piling; and I do hereby declare that the following is a full, clear, and exact description thereof, reference being had to the accompanying 10 drawings, and to the letters of reference marked thereon, which form a part of this specification.

This invention relates to improvements in interlocking metal sheet piling designed for 15 use in the construction of cofferdams, retaining walls for excavations and the like, and the invention consists in the matters hereinafter set forth and more particularly pointed out in the appended claims.

20 Among the objects of my invention is to provide an improved joint between the sections or units of a sheet piling wall designed to prevent the passage of water from one side of the wall to the other.

25 Further objects of the invention are to construct and arrange the piling units in such manner as to produce a strong and rigid wall and to provide improved interlocking guides at the margins of the units 30 such as to facilitate the driving of the units.

The piling construction to which my invention is more particularly adapted embraces alternate simple and compound units, the simple units comprising web portions 35 having flanges at their side margins designed for interlocking connection with the marginal parts of the compound units, and the compound units embracing rigidly connected, laterally spaced rolled shapes, between which are received the flanged margins of the simple units and having marginal flanges directed inwardly towards each other for interlocking engagement with the flanges of the simple units.

40 In the drawings:—Figure 1 is a perspective view of a fragment of a wall constructed with my improved sheet piling. Fig. 2 is a plan view thereof. Fig. 3 is a plan view of a modified form of the construction. Fig. 4 is a plan view of a further modified 50 form thereof.

As shown in the drawings, 10, 10 designate the simple units, and 11, 11 the compound units referred to. Said simple units, as herein shown, have the form of commercial I-beams, being provided at their side

5 margins with oppositely extending flanges 12, 12. The compound units are each herein shown as made of two channel bars 14, 14 spaced a suitable distance apart, with the 60 marginal flanges 15, 15 thereof at each side of the unit directed towards each other and spaced such distance apart as to receive the webs of adjacent simple units.

My improvements relate to the means for 65 rigidly connecting the members of the compound units, to means affording proper guiding connection between the interlocking parts of the simple and compound units, arranged to facilitate the driving of the 70 units, and to means for affording water tight joints between the adjacent units of the wall structure.

In the constructions shown in Figs. 1 and 2 the connection between the members of 75 the compound units comprises channel bars 16, 16, the webs of which extend transversely between the webs of the members 14 of said units, and the flanges 17 of which fit against and are attached to the inner 80 sides of said webs of the channel bar members of the compound units. The webs of the connecting channels 16 are located at such distance inwardly from the flanges 15 of the lateral members of the compound 85 units as to afford longitudinal spaces which receive the flanges 12 of the simple units 10. Said connecting channels 16 thus constitute, together with the marginal flanges 15 of the compound unit members, guides to guide 90 each unit, while it is being driven from an already placed or driven unit. The connecting channels 16 also serve to confine or hold the interlocking flanges of the units flatwise together, thus giving rigidity to the 95 wall structure and preventing inward collapsing or displacement of the wall units relatively to each other due to unequal lateral pressure against the wall. Said guiding and connecting channels 16 may be attached to the side members of the compound units through the medium of short bolts 18, 18, each extending through one of the flanges of a connecting channel bar and through the web of an adjacent compound 100 unit member. If desired, said connecting channels may be fixed to the side members of the compound units by longer bolts 19 which extend through the webs of both members of the compound units and through 105 the two flanges of a connecting channel resting thereagainst.

110

After a wall has been constructed by the use of the units described, the spaces within and inclosed by the members of the compound units are filled with a suitable packing material, such as soft clay, grout or the like, which is placed in said packing spaces when in a plastic or soft state and closely fills the same. Said packing material is of such a nature as to find its way between the 10 flanges of the connecting channels and the webs of the compound unit members, and into the spaces between the interlocking flanges of the units and said flanges and the webs of the connecting channels, and to completely fill said spaces in a manner to prevent the passage of water between the interlocking units.

Instead of employing two guiding and connecting channel bars for each compound 20 unit, I may employ a single deep flanged channel bar 20, such as shown in Fig. 3. In this instance, the flanges 21 of the channel bars are placed flat against the inner sides of the members of the compound units and 25 are attached to said members either by the short bolts 22 or the longer bolts 23. The web of each deep flanged channel bar is arranged adjacent to and parallel with the marginal flanges 15 at one side of the unit 30 to afford a space between said web and flanges to receive one of the flanged margins of an adjacent simple unit. The free margins of the flanges 21 extend towards the opposite flanges of said unit to engage and 35 guide the flanges 12 of the adjacent simple unit.

In each of the constructions just described the guiding and attaching channel bars constitute means by which the members of the 40 compound unit are fixed rigidly together. They serve to give great strength and rigidity to the compound unit, compared to the 45 unit to the compound unit, compared to the metal employed, and also serve to provide an exceedingly rigid joint between adjacent units.

In Fig. 4 I have shown the channel bars 25 arranged to serve only as guide channels, the members of the compound unit being 50 connected by bolts extending transversely through said members and guide channels. As shown in said figure the webs of said 55 guide channels are arranged parallel to the webs of the members of the compound units, and are attached thereto by bolts 27. Flanges 26 of said channels are arranged closely adjacent to and parallel with the marginal flanges 15 of the side members of the compound units to provide between said flanges 60 spaces to receive the flanged margins of the simple units. The fastening bolts 27 extend through spacing sleeves 28 which engage at their ends the webs of the guide channels

and serve to hold the side members of the compound units spaced the proper distance 65 apart, the heads and nuts of said bolts preventing said members from spreading, as is obvious.

I claim as my invention:—

1. In interlocking metal sheet piling, a 70 compound unit comprising laterally separated channel bar side members having their flanges directed towards each other, and a flanged guide bar co-extensive with the channeled side members extending between said side members inside the flanges thereof and reinforcing and connecting said side members together, parts of said guide bar opposing said flanges being arranged to form between the same and said flanges 80 spaces to receive and guide the flanged margins of an adjacent unit.

2. Interlocking metal sheet piling comprising alternate simple and compound units, the former having flanged longitudinal margins and the latter comprising two side members having flanged margins for interlocking engagement with the margins of the simple units, flanged bars extending between the members of the compound units 90 inside the flanges of the latter, said flanged bars extending continuously throughout the length of the compound units and constituting means for reinforcing said side members and for connecting the same and having parts at the sides of the longitudinal centers of the compound units between which and the flanges of the members of the compound units are provided guide spaces to receive the flanges of the simple units, the 100 parts being arranged to provide central longitudinal spaces in the compound units to receive a mass of filling material.

3. Interlocking metal sheet piling comprising alternate simple and compound 105 units, the simple units comprising I-beams and the compound units comprising channel bars arranged with their flanges directed towards but separated from each other, and channeled guide bars extending between 110 and attached at their flanged margins to the webs of said side members throughout the length of the compound units, the webs of said guide bars being arranged just inside the flanges of the channel bar side members 115 to form between said flanges and webs guide spaces to closely receive the flanges of the simple units.

In testimony, that I claim the foregoing as my invention I affix my signature in the presence of two witnesses, this 24th day of March A. D. 1908.

MANLEY W. CLUXTON.
